UNITED STATES PATENT OFFICE.

THOMAS J. MORRIS, OF RICHMOND, VIRGINIA.

UMBRELLA.

Application filed February 14, 1922. Serial No. 536,451.

To all whom it may concern:

Be it known that I, THOMAS J. MORRIS, a subject of the King of Greece, residing at Richmond, in the county of Henrico and State of Virginia, have invented certain new and useful Improvements in Umbrellas, of which the following is a specification.

This invention relates to umbrellas and has special reference to a body supported umbrella.

One principal object of the present invention is to improve the general construction of devices of this character.

A second important object of the invention is to provide an improved form of umbrella having attaching means to enable it to be carried by the user without making it necessary to use the hands thus leaving the latter free for other use as in the distribution of mail by mail carriers, telegrams by messengers and on other like occasions.

A third important object of the invention is to provide an improved form of folding umbrella for this purpose which will fold in such manner that the center moves downward in place of the ends of the ribs moving downward. In this manner the umbrella may be collapsed from a position close to the user's head.

A fourth important object of the invention is to provide a novel collapsing and expanding means for an umbrella of this type.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a perspective view of a person carrying the improved umbrella, the latter being in its expanded or spread position.

Figure 2 is a side view of a person carrying the umbrella in its collapsed position.

Figure 3 is an enlarged detail view of the housing frame and umbrella frame, certain of the parts being omitted in order to more clearly disclose the details of the device.

Figure 4 is a section on the line 4—4 of Figure 3.

Figure 5 is a section on the line 5—5 of Figure 3.

Figure 6 is a section on the line 6—6 of Figure 3.

Figure 7 is a section on the line 7—7 of Figure 5.

Figure 8 is an enlarged detail view showing the upper part of the housing frame 60 with the umbrella expanded or spread.

Figure 9 is a detail plan of the upper end of the housing frame and showing the notch and ribs of the umbrella.

Figure 10 is an enlarged detail side elevation of the upper part of the housing frame.

Figure 11 is a detail section on the line 11—11 of Figure 3.

Figure 12 is a detail perspective of part 70 of the shoulder pad.

The invention in its present embodiment consists in general of a supporting device and housing frame, an umbrella, and the operating means for the umbrella.

The supporting device and housing frame 75 consists of a shoulder pad having a body 10 shaped to fit over the shoulder of the wearer. At the outside there is provided an upstanding lug 11 and from the front edge of the frame extends a tongue 12 provided with a chain locking notch 13. From the rear edge of the shoulder pad extends a pair of upwardly directed arms 14. This shoulder pad is preferably made with a metallic frame covered with leather or other similar material so as to rest easily on the shoulder and eliminate wear on the clothing.

Carried by the arms 14 are vertical housing frame members 15 which are connected at intervals of their lengths by surrounding 90 hoops 16. On one of these members 15 is a loop 17 which is located near the lower end of the member and has secured thereto a strap 18. On the extension 12 is a similar loop 19 from which runs a second strap 20, the two free ends of the straps being adjustably connected, as by a buckle 21. It will

be observed that the straps when connected run diagonally upward across the back, under the arm pit and across the chest, this single strap thus sufficing, with the shoulder pad, to hold the housing frame upright behind the wearer's shoulder. The lower end of this housing frame is closed by a plate 22 while, on the upper end is supported a ring 23. The entire housing frame thus forms a skeleton basket. Each member 15 consists

preferably of a square tube having slots 24 extending longitudinally of two sides.

Mounted slidably on said members 15 is a 110 guide yoke 25 having its ends bifurcated to fit the tubes and centrally of the upper side

of this yoke is an arched lug 26 having the lower end of an umbrella staff 27 fixed therein.

On the upper end of this staff is mounted 5 the usual umbrella notch 28. Pivoted to the notch are the inner ends of the umbrella ribs 29 which are slotted longitudinally so as to permit sliding connection of the ribs and ring 23. As the notch is smaller than 10 the ring upward movement of this notch will not only lift the ribs but will also cause their upper ends to diverge outwardly until, from the position shown in Figures 2 and 3, the position shown in Figures 1 and 8 is 15 reached. These ribs are provided with the usual cover 30 which has a water proof center 31 preferably formed by an extra thickness of rubberized fabric.

In order to readily raise the center of the 20 umbrella and thus expand it there is provided a chain 32 one end of which is attached to the ring 23. This chain extends from its point of attachment downward and around a pulley 33 journaled in the arch of 25 the lug 26. From this pulley the chain extends upwardly and over a second pulley 34, carried by the ring 23, and then downward in front of the user's shoulder so that it may 30 be engaged in the notch 13. It is obvious that by pulling upon the chain the yoke 25, and with it the notch 28, will be raised and the umbrella expanded.

In the tubes 15 are tension springs 35 each 35 of which has its lower end anchored at the bottom of the tube and its upper end provided with a finger 36 projecting laterally through the respective slot 24. Thus when the yoke is raised it moves freely upward until it engages the fingers 36 after which it 40 moves upward against the tension of the springs 35 so that immediately upon release the yoke will be forced down and the umbrella folded or collapsed. The umbrella may be held expanded by engaging the chain 45 in the notch 13 and this is the preferable method whenever it is desired to frequently expand and collapse the umbrella. Other means are also employed to hold the umbrella raised when it is expected to be kept 50 in such position for a considerable length of time. For this purpose there is provided in each tube a dog 37 inverted on the stem of a thumb button 38. These dogs work through slots 39 in the tubes and when moved outwardly beneath the yoke engage the lower ends of said slots and thus hold the yoke 55 raised as shown in the dotted lines in Figure 7.

It is observed that the various parts of the 60 device are made from light metal after the fashion of an ordinary umbrella.

There has thus been provided a simple and efficient device of the kind described and for the purposes specified.

It is obvious that minor changes may be

made in the form and construction of the invention without departing from the material principles thereof. It is not therefore desired to confine the invention to the exact form herein shown and described, but it is 70 wished to include all such as properly come within the scope claimed.

Having thus described the invention, what is claimed as new, is:—

1. In a device of the kind described, a 75 housing frame open at the top, an umbrella in said housing frame and having its central portion within the frame and ribs projecting upwardly from said central portion, and mechanism attached to the umbrella and housing frame and arranged to raise the central portion of the umbrella frame and expand the ribs outwardly. 80

2. In a device of the kind described, a 85 housing frame open at the top, an umbrella in said housing frame and having its central portion within the frame and ribs projecting upwardly from said central portion, means to raise the central portion of the umbrella frame and expand the ribs outwardly, and spring means to depress said central portion and cause collapse of said frame. 90

3. In a device of the kind described, a 95 housing, an umbrella movable into and out of said housing, and mechanism attached to the umbrella and housing frame and arranged to move the umbrella out of the housing and cause it to expand and mechanism to move it into the housing and cause 100 it to collapse.

4. In a device of the kind described, a 105 housing frame including vertical guide members, a yoke slidable on the guide members, an umbrella provided with a staff carried by said yoke and having ribs pivotally connected at their inner ends on said staff, said housing frame including a member with which said ribs have slidable tilting connection, and means to raise and lower said 110 yoke.

5. In a device of the kind described, a 115 housing frame including vertical guide members, a yoke slidable on the guide members, an umbrella provided with a staff carried by said yoke and having ribs pivotally connected at their inner ends on said staff, said housing frame including a member with which said ribs have slidable tilting connection, and means to raise and lower said yoke, including a chain arranged to pull said yoke 120 upward and springs urging the yoke downward.

6. In a device of the kind described, a 125 housing frame including vertical guide members, a yoke slidable on the guide members, an umbrella provided with a staff carried by said yoke and having ribs pivotally connected at their inner ends on said staff, said housing frame including a member with 130

which said ribs have slidable tilting connection, means to raise and lower said yoke including a chain arranged to pull said yoke upward and springs urging the yoke downward and means to engage and hold said chain.

7. In a device of the kind described, a housing frame including vertical guide members, a yoke slidable on the guide members, an umbrella provided with a staff carried by said yoke and having ribs pivotally connected at their inner ends on said staff, said housing frame including a member with which said ribs have slidable tilting connection, means to raise and lower said yoke, and a body engaging support to which said housing frame is attached.

8. In a device of the kind described, a housing frame including vertical guide members and a top ring carried thereby, a yoke slidably mounted between said guide members, an umbrella staff fixed to said yoke, an umbrella notch carried by said staff and umbrella ribs each having a slot through which said ring is engaged and having their inner ends pivoted to said notch, said ring being of greater diameter than said notch whereby outward movement of the tips of the ribs is caused by upward movement of said notch and yoke.

9. In a device of the kind described, a housing frame including vertical guide members and a top ring carried thereby, a yoke slidably mounted between said guide members, an umbrella staff fixed to said yoke, an umbrella notch carried by said staff, umbrella ribs each having a slot through which said ring is engaged and having their inner ends pivoted to said notch, said ring being of greater diameter than said notch whereby outward movement of the tips of the ribs is carried by upward movement of said notch and yoke, and means to move said yoke up and down the guide members.

10. In a device of the kind described, a housing frame including vertical guide members and a top ring carried thereby, a yoke slidably mounted between said guide members, an umbrella staff fixed to said yoke, an umbrella notch carried by said staff, umbrella ribs each having a slot through which said ring is engaged and having their inner ends pivoted to said notch, said ring being of greater diameter than said notch whereby outward movement of the tips of the ribs is carried by upward movement of said notch and yoke, and means to move said yoke up and down the guide members including a chain arranged to raise the yoke and springs urging the yoke downward.

11. In a device of the kind described, a

housing frame including vertical guide members and a top ring carried thereby, a yoke slidably mounted between said guide members, an umbrella staff fixed to said yoke, an umbrella notch carried by said staff, umbrella ribs each having a slot through which said ring is engaged and having their inner ends pivoted to said notch, said ring being of greater diameter than said notch whereby outward movement of the tips of the ribs is carried by upward movement of said notch and yoke, means to move said yoke up and down the guide members including a chain arranged to raise the yoke and springs urging the yoke downward, and means to engage and hold the chain in adjusted position.

12. In a device of the kind described, a housing frame including tubular guide members provided with longitudinal slots and a top ring fixed to the upper ends of said guide members, a yoke having bifurcated ends engaging said guide members for sliding movement thereon, an umbrella staff fixed to said yoke, umbrella ribs each having a longitudinal slot through which said ring passes, an umbrella notch on said staff to which the inner ends of said ribs are pivoted, the tips of the ribs being arranged to project upwardly when the umbrella is collapsed, springs each held in a guide member and having its lower end anchored therein and its upper end provided with a finger projecting through the slot in the guide member, and means to raise the yoke and hold it in raised position.

13. In a device of the kind described, a housing frame including tubular guide members provided with longitudinal slots and a top ring fixed to the upper ends of said guide members, a yoke having bifurcated ends engaging said guide members for sliding movement thereon, an umbrella staff fixed to said yoke, umbrella ribs each having a longitudinal slot through which said ring passes, an umbrella notch on said staff to which the inner ends of said ribs are pivoted, the tips of the ribs being arranged to project upwardly when the umbrella is collapsed, springs each held in a guide member and having its lower end anchored therein and its upper end provided with a finger projecting through the slot in the guide member, and means to raise the yoke and hold it in raised position, comprising a chain arranged to lift the yoke, and a shoulder pad fixed to said guide members and provided with an extension having a notch to engage and hold the chain.

In testimony whereof I affix my signature.

THOMAS J. MORRIS,
